UNITED STATES PATENT OFFICE

ROBERT KNOLL, OF HORNAU IN TAUNUS, GERMANY, ASSIGNOR, BY MESNE ASSIGNMENTS, TO WINTHROP CHEMICAL COMPANY, INC., OF NEW YORK, N. Y., A CORPORATION OF NEW YORK

BASIC PRODUCT AND PROCESS OF MAKING IT

No Drawing. Application filed July 30, 1929, Serial No. 382,290, and in Germany August 13, 1928.

The present invention relates to basic products and process of making them, particularly to compounds of the following general formula:

10 wherein R stands for an aliphatic hydrocarbon residue containing at least ten carbon atoms, R₁ stands for O or NH and R₂ stands for an aliphatic residue with a tertiary amino group or for an amino group which contains at least an aliphatic residue with a tertiary 15 nitrogen atom.

These compounds are suitable for therapeutic and technical purposes and are obtained if imino ethers of higher fatty acids or the acids from which these imino ethers are 20 derived, or the esters, chlorides and amides thereof, are condensed with aromatic primary or secondary amines, containing a basic side chain with tertiary nitrogen, for instance with para- β -diethylamino-ethoxyaniline, or 25 with para-aminobenzoyl-diethylamino-ethanol or with methyldiethylaminoethyl-para-phenylene-diamine or with ethyldiethylaminoethyl-para-phenylenediamine. The process may also be carried out by condensing the 30 said acids and acid derivatives with aromatic primary or secondary amines with no basic side chain and subsequently introducing a basic side chain into the products thus obtained.

35 The following examples serve to illustrate my invention, but they are not intended to limit it thereto.

(1) 10.4 g. of para- β -diethylaminoethoxyaniline, dissolved in 40 ccm. of dry acetone 40 and 15 g. of the chloride of oleic acid dissolved in 20 ccm. of acetone are mixed while cooling. After having allowed the mixture to stand for some time the hydrochloride of 45 oleylanilide precipitates in the form of white laminæ, which, when recrystallized from acetone, melts at 85° C.-87° C. By treating it with an alkali the free base is obtained as a fat-like mass. The aqueous solutions of the salts, for instance of the benzoate, the lactate, 50 or the salt of the para-phenolsulfonic acid,

yield jellies, even when only slightly concentrated.

The product has the following formula:

Instead of the chloride of oleic acid there may also be subjected the imino ethers of the same acid to reaction with the amine under 60 the same conditions. There may also be employed the corresponding acids, esters and amides, in which case it is, however, preferable to work at a temperature between 200° C. and 250° C. with or without applying pressure. 65

(2) 20.8 g. of para- β -diethylaminoethoxyaniline are mixed with 200 ccm. of acetone and a solution of 27.4 g. of the chloride of palmitic acid in 30 ccm. of acetone is gradually added thereto. After cooling the mass is 70 filtered by suction. The resulting hydrochloride which is obtained in the form of colorless laminæ, melts at 108° C.-111° C. By treating it with an alkali the base is obtained, which recrystallizes from acetone alcohol in the form of felted needles melting at 82° C. 75

The product has the following formula:

(3) 11.8 g. of the diethylaminoethanol ester of para-aminobenzoic acid are dissolved 85 in 20 ccm. of acetone and there are added 13.7 g. of the chloride of palmitic acid in 20 ccm. of acetone. After cooling, the solution is filtered by suction. The hydrochloride of the new compound, when recrystallized from acetone, is obtained in the form of white laminæ melting at 116° C. 90

The product has the following formula:

(4) 22.1 g. of asymmetric methyldiethylaminoethyl-para-phenylene-diamine dis- 100

solved in 100 ccm. of acetic ester and 30 g. of the chloride of oleic acid in 50 ccm. of acetic ester are mixed. On cooling, the hydrochloride of the new compound crystallizes in the 5 form of colorless laminae.

The product has the following formula:

(5) 64.7 g. of asymmetric ethyldiethylaminoethyl-para-phenylenediamine in 450 ccm. of dry acetone are gradually mixed with 75 15 g. of the chloride of palmitic acid in 250 ccm. of acetone. After cooling, the hydrochloride of the new compound crystallizes in the form of white druses melting at 81° C.

The product has the following formula:

25 I claim:

1. The process which consists in causing a derivative of a higher fatty acid of the general formula:

wherein R stands for an aliphatic hydrocarbon residue containing at least 10 carbon atoms, R₁ stands for a radical of the group 35 consisting of OH, OCH₃, OC₂H₅, OCH₂C₆H₅, Cl, NH₂ and R₂ stands for O or NH, to act upon an aromatic polyamino compound of the following general formula:

wherein R₃ stands for an aliphatic residue with a tertiary amino group or for an amino 45 group which has at least one aliphatic residue containing a tertiary nitrogen.

2. The process which consists in causing a chloride of a higher fatty acid of the general formula:

wherein R stands for an aliphatic hydrocarbon residue with at least 10 carbon atoms, 55 to act upon an aromatic polyamino compound of the following general formula:

wherein R₃ stands for an aliphatic residue with a tertiary amino group or for an amino group which has at least one aliphatic residue containing a tertiary nitrogen.

65 3. The process which consists in causing a

chloride of a higher fatty acid of the general formula:

7 wherein R stands for an aliphatic hydrocarbon residue containing at least 10 carbon atoms, to act upon a compound of the general formula:

7 wherein R₁ stands for hydrogen, an alkyl or an aralkyl and R₂ stands for an aliphatic residue containing a tertiary nitrogen atom.

4. The process which consists in causing a chloride of a higher fatty acid of the general formula:

8 wherein R stands for an aliphatic hydrocarbon residue containing at least 10 carbon atoms, to act upon a compound of the formula:

9 wherein R stands for CH₃ or C₂H₅.

5. As new products, the compounds of the following formula:

10 wherein R stands for an aliphatic hydrocarbon residue containing at least 10 carbon atoms, R₁ stands for O or NH and R₂ stands for an aliphatic residue with a tertiary amino group or for an amino group which contains at least one aliphatic residue with a tertiary nitrogen atom, said products possessing valuable therapeutic and technical properties.

6. As new products, the compounds of the following formula:

11 wherein R stands for an aliphatic hydrocarbon residue containing at least 10 carbon atoms, R₁ stands for hydrogen or alkyl and R₂ stands for an aliphatic residue with a tertiary nitrogen, said products possessing valuable therapeutical and technical properties.

7. As new products, the compounds of the following formula:

12 wherein R stands for an aliphatic hydrocarbon residue containing at least 10 carbon atoms, said products possessing valuable therapeutic and technical properties.

8. As a new product, the compound of the following formula:

said products possessing valuable therapeutic and technical properties.

10 In testimony whereof, I affix my signature.
ROBERT KNOLL.
